Co-pending design U.S. Appl. No. 29/766,031, filed Jan. 13, 2021.

Primary Examiner — T Chase Nelson

(74) *Attorney, Agent, or Firm* — Greer, Burns & Crain, Ltd

(57) **CLAIM**

The ornamental design for a footwear outsole as shown and described.

DESCRIPTION

FIG. 1 is a front perspective view of a footwear outsole showing my new design;

FIG. 2 is a side elevational view thereof;

FIG. 3 is an opposite side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The broken lines in FIGS. 1-7 represent unclaimed environmental structure in the form of a footwear upper and midsole as well as portions of the footwear outsole that form no part of the claimed design.

1 Claim, 7 Drawing Sheets
